MASSAGING DEVICE

Roland A. Reid, Chicago, Ill.

Application February 20, 1946, Serial No. 648,856

9 Claims. (Cl. 128—57)

1

This invention relates to a manually operable massaging device whereby massaging with or without the use of massaging creams and the like may be efficiently accomplished.

The present invention, more specifically, pertains to a massaging apparatus including a manually operable padded or chambered support having a multiple roller-type massaging unit adapted to travel back and forth on the support and at the same time pick up and distribute a massaging cosmetic when the apparatus is in use.

It is an object of this invention to provide an improved apparatus for conveniently massaging parts of the human anatomy by means of a multiple-type roller massaging carriage adapted to freely travel back and forth on a suitable support when the massaging apparatus is manually applied and actuated over an area requiring massaging.

Another object of the invention is to provide a manually operable massaging device wherein a multiple-type traveling roller carrying carriage is adapted to be operated to cause the rollers to pick-up and feed a massaging cosmetic over an area being massaged by the rollers.

It is a further object of this invention to provide an improved and simplified type of hand operated massaging device wherein massaging rollers are connected to one another in spaced relationship to cause all of the rollers to be moved back and forth over an area being massaged when the device is manually reciprocated.

It is a further object of this invention to provide an improved and simplified form of manually operable massaging device wherein one or more massaging rollers are slidably mounted to freely travel on the applicator end of a massaging unit to distribute and apply a massaging medium over an area on which the device is applied.

It is an important object of this invention to provide a simple, inexpensive and efficient type of manually operated massaging apparatus wherein massaging rollers are rotatably supported on connected hangers to cause all of the rollers to be freely moved in unison either backwardly or forwardly on a suitable guide forming a part of the massaging apparatus when the apparatus is manually operated over an area to be massaged.

Other and further important objects and features of this invention will be apparent from the disclosures in the specification and the accompanying drawings.

In the drawings:

2

Figure 1 is an isometric view of an improved massaging device embodying the principles of this invention.

Figure 2 is a transverse detail section of the same taken on line II—II of Figure 1.

Figure 3 is a fragmentary longitudinal sectional view through the massaging end of a modified form of massaging apparatus.

Figure 4 is a top plan view of the modified form of massaging apparatus illustrated in Figure 3, and showing the movement of the slidable top in dotted lines to facilitate filling of the chambered applicator head forming a part of the modified device.

Figure 5 is a transverse detailed section of the modified form of massaging device taken on line V—V of Figure 4.

As shown on the drawings:

Figures 1 and 2 illustrate one form of an improved massaging device, of the manually operable type and comprising a handle 1 deflected or offset at 2 to form a stop shoulder. Integrally formed on or rigidly secured to the stop shoulder 2 is an applicator or guide head 3 which serves as a support as well as a guide member for a massaging carriage or unit. A cushion or pad 4 constructed of any suitable selected material is tightly secured or stretched across the bottom surface of the guide head 3. The pad 4 forms a runway as well as a massaging material supply source for a plurality of hollow massaging rollers 5. The rollers 5 may be constructed of soft or hard rubber or any other suitable material such as plastic or out of metal if preferred. Each of the rollers 5 is rotatably supported on the oppositely projecting shaft ends 6 of a bracket or frame 7 which may be constructed of wire or suitable material and is of rectangular formation to permit the bracket or frame to be slidably engaged over the applicator head 3 and the pad 4 secured thereto.

As illustrated in Figure 1, the applicator carriage or unit consists of three massaging rollers and three brackets, with said brackets held in spaced relationship with respect to one another by means of a connector 8 constructed of wire or other suitable material and comprising three equi-distantly spaced loops 9 through which the respective roller-carrying brackets 7 have the top members thereof engaged. It will thus be noted that the roller units are held in spaced relationship and are connected one to the other to form a traveling applicator carriage which is adapted to freely move back and forth on the guide head

3 when the massaging end of the device is moved over an area to be massaged.

When desired, the cushion or pad 4 may be constructed of an absorbent material and may be saturated with or have a massaging cream or a cosmetic applied thereto so that when the massaging rollers 5 roll over the cushion 4, they will pick up a quantity of the massaging material and distribute the same over the area which is being massaged by causing the rollers to be moved back and forth over the area with the reciprocating movement of the device by means of the handle 1.

Referring to Figures 3, 4, and 5, a modified form of massaging apparatus is illustrated. The modified massaging device comprises a handle 10 having rigidly secured on one end thereof an applicator guide head 11 in the form of an elongated trough or container formed with a chamber 12 having a plurality of outlet apertures 13 provided therein at spaced intervals. The feed apertures 13 may be of any selected size, depending upon the kind of cosmetic to be used. One end of the chambered guide head 11 is rigidly secured to the handle 10 to permit movement of the guide head over an area to be massaged.

The side walls of the applicator guide head 11 are grooved or bent inwardly to provide guide slots or grooves for the slidable reception of the longitudinal edges of a cover plate 14. One end of the cover plate 14 is curled to provide a handle 15 to permit slidable operation of the cover plate.

The top surface of the inner end of the cover plate 14 is provided with a latching recess or notch 16 located to removably receive the end of a spring latch 17 formed on the supported end of the guide head at the top of the end wall thereof to lockingly snap into the recess or notch 16 when the cover plate is moved into closed position to close the chamber 12 of the applicator guide head.

The chamber 12 of the applicator head 11 is adapted to carry a supply of beauty cream 18 or other cosmetic which is permitted to gradually be fed out through the apertures 13 to be picked up and distributed by means of a plurality of massaging rollers 19 which are positioned to roll over the bottom apertured surface of the applicator head 11. Each of the rollers is rotatably supported on an open loop bracket 20 with the ends of the bracket projecting inwardly toward one another and serving as a support for a roller. The roller carrying brackets 20 are slidably engaged over the massaging head 11 and the cover plate 14 thereof and have the top portions disposed transversely of a connecting plate or bar 21 having gripping fingers or lugs 22 struck upwardly therefrom and bent or hooked over the top members of the brackets 20. The brackets 20 are thus held in spaced relation with respect to one another and are permitted to hang and have a swinging movement. The connecting plate 21, the brackets 20 and the rollers 19 are connected to form a massaging carriage which is adapted to travel back and forth on the applicator head when the massaging device is in operation and is moved back and forth over an area to be massaged. The massaging end of the device is, of course, adapted to be operated by means of the handle 10 so that the rollers may be lightly applied to a massaging surface or said rollers may have pressure exerted thereon for more strenuous application of the rollers when necessary.

It will thus be seen that an improved massaging device, of the manually operable type, is provided

whereby an applicator head is adapted to be moved back and forth over an area to be massaged to cause a multiple-type roller carrying applicator mechanism to travel back and forth on the applicator head with the movement thereof to cause the plurality of rollers to thoroughly massage the area requiring treatment. It will thus be noted that the traveling carriage carrying a plurality of rollers provides an arrangement whereby a plurality of adjacently positioned smaller areas may be massaged simultaneously, depending upon the number of rollers carried by the traveling carriage.

Attention is called to the fact that in the two forms of massaging devices disclosed that a cosmetic in the form of a cream or the like may be picked up and distributed by the massaging rollers when a cosmetic is carried on the cushion or pad 4 or in the supply chamber 12 of the applicator guide head 11.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A massaging device comprising a handle, a rigid applicator guide head secured thereto and operable thereby, and a plurality of freely rotatable massaging elements mounted to travel in grouped relationship back and forth on the guide head when the same is caused to travel over an area to be massaged.

2. A massaging device comprising a handle, an applicator guide head secured thereto and operable thereby, a carrier mounted to travel over the exterior of the guide head when the same is moved over an area to be massaged, and a massaging element rotatably supported on the carrier and adapted to rotate and swing by contact with the guide head and said area to massage the area when the guide head is actuated by means of the handle.

3. An article of manufacture a massaging device comprising a rigid applicator guide head, a handle for operating the same, a plurality of frame members surrounding the guide head and mounted to travel on the guide head, massaging elements rotatably carried by the frame members and adapted to swing and be rotated by contact with the guide head and an area to be massaged when the guide head is actuated by means of the handle, and a connector on said guide head connecting the frame members to hold the massaging elements in spaced operating relationship.

4. A massaging device comprising a handle, a guide head secured thereto and operable thereby, a cosmetic carrying means on the guide head, a plurality of frame members surrounding and loosely engaged to travel on the guide head, means slidably on the guide head for holding the frame members in spaced relationship, and massaging elements rotatably carried by the frame members and rotatable over an area to be massaged and over the cosmetic carrying means when the guide head is operated by the handle, said massaging elements when rotated acting to feed a cosmetic from the cosmetic carrying means to the area being massaged.

5. A massaging device comprising a guide head, means for operating the same over an area to be massaged, a plurality of frame members loosely surrounding the guide head and adapted to travel

thereon, a connector slidable on the guide head and holding the frame members spaced from one another, a cosmetic holder forming a part of the guide head, and massaging elements rotatably carried on the frame members and movable over the cosmetic holder and over the area to be massaged to feed the cosmetic to said area when the massaging device is operated over the area.

6. A massaging device comprising a rigid guide head, means for operating the same over an area to be massaged, a carriage slidably mounted to travel on top of the guide head, and massaging elements rotatably and swingingly supported on the carriage and rotatable between the guide head and said area when the device is moved over the area.

7. A massaging device comprising a cosmetic carrying guide head, means for operating the same over an area to be massaged, a member slidably mounted on the guide head, a plurality of hangers pivotally carried by said member and surrounding the guide head, and massaging rollers rotatably supported on said hangers and adapted to feed the cosmetic to the area while massaging the same when the device is operated over the area.

8. A massaging device comprising a guide head, means for operating the same back and forth over an area to be massaged, a member mounted to

freely travel on the guide head when the same is in operation, and a plurality of massaging elements pivotally and rotatably carried by said member and rotatable between the guide head and said area to massage the area when the device is operated.

9. A massaging device comprising a rigid guide head, means for operating the same over an area to be massaged, a member longitudinally and transversely movable on the guide head, hangers pivotably and slidably supported on said member and surrounding the guide head, and massaging rollers rotatably carried by said hangers.
